(Cl. D48—32)

FIG. 1

FIG. 2

FIG. 3

FIG. 5

FIG. 4

FIG. 1 is a top plan view of a clearance lamp for commercial automotive vehicles embodying my new design;

FIG. 2 is a side elevational view thereof;

FIG. 3 is a bottom plan view thereof, with a portion of the base broken away to better show the configurational details thereof;

FIG. 4 is an end elevational view thereof; and

FIG. 5 is a fragmentary sectional view thereof, taken on the line 5—5 of FIG. 1, and showing the transverse configurations of the grooves of FIG. 1.

I claim:

The ornamental design for a clearance lamp for commercial automotive vehicles, substantially as shown.
